SMOKER'S ASH AND STUMP RECEIVER
AND ISOLATOR

John R. Furman, Kerrville, Tex.

Application February 16, 1943, Serial No. 476,053

3 Claims. (Cl. 220—20.5)

1

This invention relates to tobacco users appliances, especially to an improved and simplified type of smoker's ash and stump receiver and isolator.

One object of the invention is to provide a device of this kind that is capable of being formed of very few and simple units that are integrally formed by molding or casting or pressing into their respective shapes with very simple dies or molds, of one or more relatively inexpensive and light-weight materials, for instance, glass, porcelain or other ceramic material, Bakelite or other plastic material, and which units are quickly and easily assembled and retained in mutual operative engagement and normally fixed relation to one another without the use of any extrinsic securing means, and which are operable by mere manual lifting of one of these units and by gravitation of the latter to its normal position on the other units.

Other objects and important features are pointed out or implied in the following details of description, in connection with the accompanying drawings in which:

Fig. 1 is a vertical central sectional view of one form of the invention in its normal relation of its component units, the broken line circle representing the position of a cigar-stump in the primary receptacle.

Fig. 2 is a view similar to Fig. 1, except the housing-unit being in a sufficiently raised position to permit the cigar-stump to fall from the closure-unit into the lower part of the base-unit or secondary receiving vessel, as indicated by the broken line circle.

Fig. 3 is a top plan view of the device shown in Figs. 1 and 2, a part of the housing-unit being broken away to disclose the interior of the housing unit, the subjacent wall-portion of the base-unit, and the adjacent end of the closure-unit resting on the said wall-portion.

Fig. 4 is a central vertical sectional view of a modified form of the invention, the housing-unit being shown in its normal position in broken lines, and in its raised position in full lines, the broken line circle indicating the position of a cigar-stump about to fall from the closure-unit.

Fig. 5 is a top plan view of the closure-unit shown in Figs. 4 and 6.

Fig. 6 is a top plan view of the embodiment shown in Fig. 4.

Fig. 7 is a second modified form of the invention, in central vertical section, the housing-unit being shown raised, as shown in full lines, to permit the ash and stumps to fall from the primary receptacle into the secondary receptacle, vessel or

2

base-unit; the broken line circles showing positions of two cigar-stumps passing from the closure of the primary receptacle; the other broken lines showing the normal lower position of the housing-unit.

Fig. 8 is a top plan view of the modification shown in Fig. 7.

Referring to these drawings in detail, in which, similar reference numerals refer to similar parts in the several views, the invention is described in detail as follows:

The base-unit is shown at 10, 10a and 10m in the respective forms of the invention; while the housing-unit is shown respectively at 11, 11a and 11b; and the closure-element is shown at 12, 12a and 12b, respectively.

In each of these forms of the invention there are only three primarily separate elements as follows: In Figs. 1-3, the elements or units 10, 11 and 12 are primarily separate from one another, the base-unit 10 being formed with arched seats 10c on opposite walls or wall-portions which are lower at their middle portions than are the other opposite walls or wall-portions, and opposite ends 20 of the elongated closure-unit 12 normally rest on these arched seats, being retained in this normal position (of Fig. 1) by stops or lugs 12c that are against or very near to the wall-portions or seats 10c, and prevented from rocking by the wall-portions 11c that normally rest on the laterally inclined longitudinal edges of the closure 12. The wall-portions 11c adjoin the wall-portions 11d at a distance from the wall-portions 11e and 11f, and these wall portions 11d also normally rest on 30 the closure 12 and combine therewith to form a primary receptacle for all such smoker's refuse as ash, stumps, match-stems, etc.; but when the unit 11 is sufficiently raised, as seen in Fig. 2, the primary receptacle is opened to permit the refuse to 35 pass laterally of the closure 12 and down from the lateral sides of the closure to the bottom of the vessel or secondary receptacle 10; and as a cigar-stump rolls or slips to either one of the inclined edge-portions of the closure 12 its weight causes 40 the closure to tilt, as seen in Fig. 2, thereby tending to dump any ash that may be adhering to the closure; but when the closure is freed from such weight, it automatically rocks to and fro (laterally), thus tending to free it from some or all of 45 the remaining ash on the closure. Moreover, when the unit 11 is permitted to gravitate to its normal position, the wall-portions 11c and 11d, upon striking the closure 12, tends to loosen any 50 remaining ash and cause it to pass laterally in 55 readiness to be dumped when the unit 11 is again

raised. The several purposes and functions of the wall-portions $11f$ are to serve as a convenient means to grasp for lifting the wall-portions of the primary receptacle, to keep the primary receptacle's wall-portions properly disposed with reference to the closure 12 and guide the wall-portions $11c$ and $11d$ into proper normal position on the closure, and to prevent burning of the fingers of a user in case of a lighted match or an unquenched cigar-stump causing a blaze in the vessel 10 .

In Figs. 4, 5, 6, there is a notch $10g$ in each of the two opposite wall-portions, and the closure $12a$ has two end-extensions $12g$ normally fitting loosely in these notches in the proper relation, shown in Fig. 4, for supporting the major portion of the closure in the inclined position shown. Wall-portions $11g$ and $11h$ (Fig. 4) normally rest on the closure-unit $12a$ and combine therewith to form the primary receptacle for refuse; but when the housing-unit $11a$ is sufficiently raised, the refuse rolls or slides under the wall-portion $11g$ and off the lower-lateral edge of the closure and falls to the bottom of the vessel or secondary receptacle $11a$.

Both the closures 12 and $12a$ are normally secured in their respective closing positions, but are free to be lifted upward and away from their normally seated positions when the housing-units have been moved out of the way, so full and free access is then had to the interior of the vessel or secondary receptacle so the refuse can be easily removed and said interior can be thoroughly washed.

The second modification (Figs. 7 and 8) is designed for casting or molding the element $12b$ integrally with the wall-portions $10j$ and $10k$, also for dumping two or more cigar stumps simultaneously, by one lift of the housing-unit $11b$, as indicated in Fig. 7 where two broken line circles indicate the circumferences of two cigar stumps leaving the primary receptacle for deposit in the secondary receptacle or chamber $10b$. In casting or molding the parts $10j$, $10k$ and $12b$ integrally without undue expense, it is important that the lower end of this integral element be primarily open, and subsequently closed by the bottom element $10m$ which is preferably in the shape of an inverted bowl or pan having an endless V-shaped groove or rabbet $10r$ that constitutes a seat for the lower edge-portions of the elements $10j$ and $10k$ which are preferably secured in place permanently by means of plaster of Paris, Portland cement, or any other suitable cementing material or other means. The wall-portions of the element $10m$ provide a convenient handle or gripping portion that is exposed below the wall-portions $11w$ and $11x$ in both the raised and normal lower positions of the housing-unit $11b$, so the whole device can be quickly lifted and moved from place to place without first raising the housing unit from its normal position wherein the wall-portions $11y$ and $11z$ rest on the closure element $12b$ and combine therewith to constitute the primary receptacle for refuse of a smoker or smokers.

Though I have shown each of these forms of the invention substantially cubic and rectangular

in plan and horizontal section, it is quite within the scope of this invention to make it in other angular shapes or in curved contour; and while I have indicated the material as being glass, porcelain etc., the invention is not limited to any specific kind or kinds of materials. The different forms are shown with depressed portions that are deeper at their inner ends than elsewhere, to serve as cigar-seats or rests which serve to keep the cigars therein from sliding outward in consequence of vibrations etc., but the invention is not limited to this form of cigar-rests, nor limited to any of the specific and exact details of description or illustration; for the invention is susceptible of numerous changes within the scope of the inventive ideas as implied and claimed herein. Moreover, while these forms and sizes of the invention are designed for cigar-smokers' use, each can be made smaller for use of cigarette smokers, especially for ladies who have smaller hands with which to handle and operate the device.

I claim the following as my invention:

1. In a smoker's receiver for ash, stumps, etc., the combination of a vessel having an inlet-opening at its top and having opposite wall-portions, an elongated closure normally extending from one to the other of said wall-portions and normally located on and supported by the latter at a considerable distance above the bottom of said vessel and in a proper position to provide a clear space thereunder and to close only a portion of said inlet-opening, and a housing-unit that comprises outer wall-portions and inner wall-portions and a roof which latter is united with these inner and outer wall-portions, the lower ends of these inner wall-portions of the housing having an opening between them and being normally seated on said elongated closure and thus combining with said closure to constitute a primary receptacle for ash and stumps, said outer wall-portions of the housing unit normally surrounding the middle and upper parts of said vessel and being continually in position to be grasped by a hand of a person and raised sufficiently to permit ash and stumps to fall from said closure to the bottom-portion of said vessel, said housing unit being free to gravitate from its raised position to its normal lowermost position on said closure when released from restraint of the hand that raised it.

2. The combination defined by claim 1, said closure being provided with means to secure it against accidental movement from its normal position on said opposite wall-portions but being free to be lifted from said vessel when said housing-unit has been lifted away from said vessel, whereby the user can gain free and unobstructed access to the interior of said vessel for ridding the latter from ash and stumps etc. and for washing and wiping said interior.

3. The combination defined by claim 1, said closure being mounted in proper relation to be tilted in opposite lateral directions when said housing-unit is raised therefrom, thereby to facilitate the dumping of ash therefrom.

JOHN R. FURMAN.
